DESIGN FOR A PENCIL TIP

Henry J. Roth, Brooklyn, N. Y., assignor to Eberhard Faber Pencil Co., Brooklyn, N. Y., a corporation of New York

Application March 26, 1938, Serial No. 76,114

Term of patent 7 years

To all whom it may concern:

Be it known that I, Henry J. Roth, a citizen of the United States and a resident of Brooklyn, in the county of Kings and State of New York, have invented a new, original, and ornamental Design for a Pencil Tip, of which the following is a specification, reference being had to the accompanying drawing, forming part thereof.

I claim:

The ornamental design for a pencil tip as shown.

HENRY J. ROTH.
